UNITED STATES PATENT OFFICE.

WALTER P. HENRY, OF DES MOINES, IOWA.

CABINET FOR DRYING FILMS, PLATES, AND PRINTS.

1,153,688.

Specification of Letters Patent. Patented Sept. 14, 1915.

Application filed April 27, 1914. Serial No. 834,631.

To all whom it may concern:

Be it known that I, WALTER P. HENRY, a citizen of the United States, residing in Des Moines, county of Polk, and State of Iowa, 5 have invented a new and useful Improvement in Cabinets for Drying Films, Plates, and Prints, of which the following is a specification.

This invention relates to photography 10 and has for its object to provide a new and improved cabinet for receiving and drying the films, plates, prints and the like. Under ordinary conditions the drying process for these articles consumes a great amount of 15 time and it is my purpose to reduce this necessary time to a very few minutes and thereby greatly facilitate the work.

My invention consists of certain details of construction hereinafter set forth, pointed 20 out in my claim and illustrated in the accompanying drawings in which—

Figure I shows a sectional view of my device; Fig. II shows a sectional view of a 25 part of my device, looking from a position in front of same; Fig. III shows a transverse sectional view of my device; and Fig. IV shows a detail view of a plate rack I employ.

Referring to the accompanying drawings 30 the reference 10 is used to indicate a rectangular cabinet of practically the proportions shown, and divided into upper and lower sections by the slotted partition 11. The upper section is fitted out with a plurality 35 of vertical frames 12, designed to be separately removable therefrom, and adapted to have prints, and the like, secured to either side surface, when desired. To the under surface of the lattice partition 11 are 40 secured a plurality of strips 13, each provided with numerous hooks 14 to which films 15 are designed to be secured and to depend therefrom. On the inner surface of

the rear wall of the cabinet I have mounted plate racks having a base 16, a back 17, and 45 supporting arms 18. The backs are loosely secured to the base, as are also the arms, so that, when not in use, the plate racks may be folded against the rear wall of the cabinet, as shown in Fig. IV.

At the lower extremity of the cabinet the sides and the rear wall converge, curving as shown, so that they meet to form a curved base. The forward wall of the cabinet is provided with a large opening 19 from 55 which a tube 20 extends outwardly, and in said tube is secured an electric fan 21, designed to throw air into the cabinet. The air strikes the curved base of the cabinet and is deflected and spread so as to reach, 60 in a gentle manner, all parts of the cabinet, passing through the slotted partition, to the upper section. I have also provided an outlet opening 22 in the top of the cabinet.

By the use of air blown from an electric 65 fan into my especially constructed cabinet films, plates, prints, and the like, may be thoroughly dried in a very few minutes.

Having thus described my invention what I claim and desire to secure by Letters Patent of the United States is:

A cabinet for drying films, plates and prints composed of a case having a slotted partition below its top, removable spaced vertical print holding frames seated at their 75 bottoms on the top face of the partition and engaged at their tops with the top of the case, film holding means connected to the under face of the partition, and means to supply a current of air to the case at the 80 bottom thereof.

WALTER P. HENRY.
